(57) **CLAIM**

The ornamental design for a tire for automobile, as shown and described.

DESCRIPTION

FIG. 1 is a front view of a tire for automobile showing my new design;

FIG. 2 is a top plan view thereof;

FIG. 3 is a perspective view thereof;

FIG. 4 is a left side view thereof;

FIG. 5 is a right side view thereof;

FIG. 6 is an enlarged front view thereof;

FIG. 7 is a cross-sectional view taken along line 7—7 of a front view thereof; and,

FIG. 8 is a cross-sectional view taken along line 8—8 of a front view thereof.

In the drawings, the dark stippled surface shading represents the recessed portion of the tread grooves, having a depth as best shown in FIGS. 7—8.
